UNITED STATES PATENT OFFICE.

FRANK A. CONNOLLY, OF POMPTON LAKES, NEW JERSEY.

MIXING AND COOLING MACHINE.

1,250,435.

Specification of Letters Patent. Patented Dec. 18, 1917.

Application filed January 22, 1917. Serial No. 143,793.

To all whom it may concern:

Be it known that I, FRANK A. CONNOLLY, a citizen of the United States, residing at Pompton Lakes, in the county of Passaic 5 and State of New Jersey, have invented certain new and useful Improvements in Mixing and Cooling Machines, of which the following is a specification, reference being had therein to the accompanying drawing.

10 My invention relates to improvements in mixing and cooling machines, especially adapted for the manufacture of smokeless powder; but I do not wish to limit the application of my invention to that particular 15 object, as my mixing and cooling machine is adapted for kindred uses and for the mixing and cooling of other materials than plain or smokeless powder.

20 My invention accordingly consists in a mixing and cooling machine, in which the material is treated in a rotatable drum, turning in one direction and provided with a series of obliquely arranged vanes which are secured to its inner surface, and deflect 25 the material laterally, and in which the material is acted upon by hollow agitator blades carried by and communicating with a tubular driving shaft, turning in an opposite direction, through which a current of 30 brine or other cooling liquid or semi-liquid is caused to flow, whereby the mixing and cooling of the material is simultaneously accomplished with a great degree of efficiency and safety.

35 The invention consists in the construction, arrangement and combination of the parts to be hereinafter described and particularly pointed out in the subjoined claims.

40 In the drawings,—

Figure 1 is a longitudinal sectional view of a machine embodying my invention.

Fig. 2 is a transverse section.

Fig. 3 is an end view of one of the blade 45 supporting rings.

Fig. 4 is a section on line 4—4 of Fig. 3.

Fig. 5 is an end view of the machine.

In the drawings, r indicates the frame of the machine; b is a hollow 50 shaft mounted in bearings q — q on the frame r ; c — c are tubular blades secured to and communicating with the hollow shaft b ; e is a supply pipe for the cooling medium inserted into one 55 end of the hollow shaft b ; f is a packing-nut with packing-rings of rubber

or other material f' , and hand wheel f^2 , said packing-nut f being screw-threaded on shaft b ; e' is an outlet pipe inserted into the other end of the hollow shaft b , and which is provided with a similar packing-nut f , packing rings f' similar to the packing-nut on the other end of the hollow shaft b .

60 A sprocket wheel h is keyed to the shaft b to turn said shaft in one direction. A drum a surrounds the central portion of shaft b and is rotatably held in position by packing-nuts g , provided with packing-rings g' .

70 A sprocket wheel i is bolted to the drum a and is operated to revolve the same in the opposite direction to the shaft b .

75 Stiffening rings or blade supports k are secured to collars z on the shaft b by screws t see Fig. 3.

80 Vanes d are obliquely fastened to the interior of the drum a by means of angle irons d' and d^2 .

The drum a rests upon rollers m on shafts p which are carried by hang-ers o fastened to the frame r .

85 The sprocket wheel h rests on rollers n carried by shafts n' in brackets n^2 , which are fastened to the frame r .

The sprocket wheel v (see Fig. 5) drives the drum a by means of a link belt v' which engages the sprocket 90 wheel i .

The sprocket h is driven from the sprocket wheel w by a belt w' ; wheels v and w are geared together so as to revolve the drum and shaft in opposite directions.

95 A cooling medium is forced into the pipe e and flows through the shaft b and blades c , the direction of its flow being determined by stoppers l , the medium finally escaping through outlet pipe e' .

100 Power may be supplied to drive the sprockets wheels v and w in any suitable manner.

105 The material in the drum of my mixing machine is not permitted to lie in an inert mass. It is kept constantly in agitation. The tubular blades revolving in one direction and the drum revolving in the opposite direction, co-acting with the obliquely ar-110 ranged vanes, act to thoroughly and safely mix the material while at the same time keeping it cool.

The material is inserted into the drum through the door $-j-$ provided with a handle $-j'$, the door being used when in the lowest position, as shown in Fig. 1, to remove the material and when in its highest position to insert the material.

The brine, passing through the tubular shaft and blades flows in the direction shown by the arrows in Fig. 1, as determined by the 10 stoppers $-l-l-$.

The roller bearings $-m-$ for the drum $-a-$ and the roller bearings $-n-$ for the wheel $-h-$, facilitate the operation of the machine, the material in the revolving drum 15 being deflected in one direction laterally, and at the same time being carried forward in the direction of the rotation of the drum, is met while falling from the vanes, by the tubular blades which are revolving in the opposite 20 direction and hence the material is quickly and thoroughly mixed and, while being so mixed, the material is cooled by the flow of brine or other cooling liquid or semi-liquid, which is passing through the tubular shaft 25 and tubular blades.

With this description of my invention, what I claim is:—

1. A mixing and cooling machine, comprising a drum provided with obliquely arranged internal vanes, a hollow shaft, 30 adapted to receive a cooling medium, passing through said drum, hollow blades radially and parallelly mounted on said shaft,

and means to rotate said drum and shaft in opposite directions.

2. A mixing and cooling machine, comprising a frame, a drum rotatably mounted in said frame, means whereby material can be fed into and removed from said drum, a hollow shaft, adapted to receive a cooling 40 medium rotatably mounted in said frame and passing centrally through the same, radial pipes carried by said shaft, connections between the outer ends of adjacent ones of said radial pipes, obstructions in 45 said shaft to cause said medium to traverse said pipes and connections, and means to rotate said drum and shaft in opposite directions.

3. A mixing and cooling machine, comprising a frame, a hollow shaft journaled therein, and adapted to receive a cooling medium, flanged collars secured to said shaft, a drum rotatably supported within the flanges of said collars, means to rotate said 55 drum and shaft in opposite directions, and agitator blades, consisting of radial pipes connected at their outer ends, secured to and communicating with said shaft.

In testimony whereof I affix my signature 60 in presence of two witnesses.

FRANK A. CONNOLLY.

Witnesses:
